UNITED STATES PATENT OFFICE.

LEO I. HEINTZ, OF PHILADELPHIA, PENNSYLVANIA, ASSIGNOR TO HEINTZ MANUFACTURING COMPANY, OF PHILADELPHIA, PENNSYLVANIA, A CORPORATION OF PENNSYLVANIA.

METHOD OF BENDING METAL.

Application filed April 30, 1923. Serial No. 635,478.

To all whom it may concern:

Be it known that I, LEO I. HEINTZ, a citizen of the United States, residing at Philadelphia, in the county of Philadelphia and State of Pennsylvania, have invented certain new and useful Improvements in a Method of Bending Metal, of which the following is a specification.

This invention relates to metal working, and more particularly to a method of producing from sheet metal hollow articles which have longitudinal curvature and which are entirely or approximately closed in cross-section.

In my Patent No. 1,525,936, dated Feb. 10, 1925, I have disclosed and claimed articles of manufacture which are particularly well adapted for use as sills in vehicle body frames and which are constructed of a single integral piece of sheet metal shaped so as to be closed and hollow in cross-section and to be longitudinally curved, thus forming in effect a closed box girder having desired longitudinal curvature. Heretofore articles of similar construction have been constructed by shaping a plurality of separate pieces of sheet metal and then securing such pieces together by bolting or welding. It is my aim to provide a method of producing articles of the character referred to from a single integral piece of sheet metal. Another object of my invention is to provide a method whereby articles having hollow and closed cross-section and longitudinal curvature may be produced from a single piece of sheet metal quickly, economically and accurately, and to the shape and size desired. Another object of this invention is to provide a method whereby a sheet metal article having a hollow and closed cross-section may be curved longitudinally without cracking or otherwise damaging the article, and without altering its cross-sectional contour. A further object of this invention is to provide apparatus and appliances adapted for use in connection with the practice of the method above described. Other objects will be in part obvious and in part pointed out hereinafter.

In accordance with my invention, I first

shape a single integral piece of sheet metal of suitable length and width transversely into the final cross-sectional shape desired by bending the sheet about a straight core or form which is shaped to give the sheet such cross-sectional contour. The core, however, is flexible, and I then bend the core or mandrel form, together with the closely enveloping shaped sheet metal, longitudinally to give the shaped sheet of metal the longitudinal curvature desired in the final article, which is now finally and completely formed. As a final operation I draw the flexible mandrel lengthwise out of an open end of the enveloping shaped article without altering either its cross-sectional or longitudinal shape. The simplicity of the method is self-evident, and results in the production of an article consisting of a single integral piece of sheet metal and which has heretofore consisted of a plurality of sheet metal pieces joined together.

In order that a clearer understanding of my invention may be had, attention is hereby directed to the accompanying drawings, forming a part of this application and illustrating one possible embodiment of my invention. For purposes of illustration I have chosen to describe specifically and to illustrate one manner of practicing my invention for the production of side sills for vehicle body frames, such sills being described and illustrated in my said patent. Referring to the drawings, Figure 1 is a plan view of a sheet metal blank from which a sill member is to be constructed; Fig. 2 is a perspective view of said sheet after it has been subjected to a preliminary transverse bending or shaping operation; Fig. 3 is a side view of a mandrel or core inserted into the sheet so shaped; Fig. 4 is a side view of the sheet bent transversely about the mandrel and into its final closed cross-sectional shape; Fig. 5 is a side view of the sill bent longitudinally to the final shape desired, the mandrel still being enclosed by said sheet and bent to the same curvature; Fig. 6 is a side view of the sheet of metal in the shape shown in Fig. 5 except that the mandrel has been removed; Fig. 7 includes,

is separate side and end views, a pair of die members adapted to be used to give the desired longitudinal curvature to the sheet metal sill while the mandrel is contained therein; Fig. 8 includes, in separate front, side and top views, a central unit of the mandrel or core; Fig. 9 includes, in separate front, side and top views, an end member of said mandrel or core; Figs. 10 and 11 are sectional views of the completed sill, and are taken respectively on lines 10—10 and 11—11 of Fig. 6; Fig. 12 is a top view of a modified form of sill which may be produced by the method of my invention; and Fig. 13 is a side view of said modified sill. Similar reference characters refer to similar parts throughout the several views of the drawings.

Referring to the drawings, in Figs. 6, 10, 11, 12, and 13 I have shown metallic frame members suitable for use in vehicle body frames, which frame members may be constructed by following the method of my invention. Two modifications of such frame members are shown, differing from each other only in that the frame member 1 illustrated in Fig. 6 is curved longitudinally in one plane only, as at 2, while in the other modification the frame member 3 has longitudinal curvature in two different planes, as at 4 and 5. From end to end these frame members are of hollow, closed, transverse cross-section, each forming in effect a box girder consisting of a single integral piece of sheet metal. If desired, these frame members may be constructed with horizontal juxtaposed flanges 6 along the longitudinal edges of the shaped piece of sheet metal, and these flanges may be secured together by welding or by other suitable means.

The principal feature of novelty of my invention is the production of such frame members from a single integral piece of sheet metal. In carrying out the method I provide a blank 7 of sheet metal of suitable shape and size, and by a suitable stamping or bending operation bend this blank 7 transversely into channel shaped form, as at 8, Fig. 2. I now provide a device which is inserted into the channel of the channel shaped piece 8, and which serves as a form about which the sheet 8 may be bent transversely. I now bend the sheet metal about this device 9 by a suitable stamping or bending operation to form the sheet metal into the hollow, substantially closed, transverse cross-sectional shape which is desired in the final article. The flanges 6 may be bent up and brought together during this operation.

The device 9 above referred to has the same transverse peripheral shape as the interior transverse shape desired in the final article; and when the piece of sheet metal has been transversely formed to shape about this device 9, serving as a form, the device

9 will completely fill the hollow in the member and reenforce the same during the next operation, which gives longitudinal curvature to the member.

To permit longitudinal curvature to be given to the sheet metal member while the device 9 is enclosed therein, the device 9 is so constructed that it is flexible. To this end the device 9 is constructed of a plurality of rigid units 10 which are strung together by means of flexible material, such as flexible wires 11, which extend through perforations in the various units. The sheet metal member of final cross-sectional shape, together with the flexible device 9 enclosed therein, is seated in a suitable die 12 which is adapted to close thereupon and bends the shaped sheet metal together with the enclosed device 9, to give the desired longitudinal curvature to the sheet metal. During this operation the device 9 acts as a reenforcing mandrel for the sheet metal and serves to maintain the transverse cross-sectional shape previously given thereto. The frame member of the desired cross-sectional and longitudinal shape corresponding to the form shown in Fig. 6 has now been produced, and the final step consists in withdrawing the flexible mandrel 9 out of an open end of the completely formed member without altering either the cross-sectional shape or the longitudinal curvature of this member. Since the mandrel 9 is flexible, this may be accomplished readily by a pulling operation.

To provide a frame member having longitudinal curvature in two planes, after the member with the mandrel 9 enclosed therein has been given longitudinal curvature in one direction, as by means of dies 12, it is bent in the other desired plane by a similar step 105 involving the use of the same or another set of dies. In this manner the member may be given longitudinal curvature in as many directions as is desired, the mandrel 9 not being removed from the member until all 110 such bending operations have been completed.

Obviously the method of this invention is not limited to use for the production of frame members for vehicle bodies, but may 115 be employed as well for the production of articles adapted for other uses.

As many changes could be made in the above construction and as many apparently widely different embodiments of this invention could be made without departing from the scope thereof, it is intended that all matter contained in the above description or shown in the accompanying drawings shall be interpreted as illustrative and not in a 125 limiting sense.

What I claim is:—

A method of the character described, which consists of bending a piece of sheet metal transversely about a flexible mandrel 130

comprising flexibly connected rigid units to give said sheet a substantially closed, hollow, cross-sectional shape, and bending said shaped sheet and mandrel longitudinally to 5 give said shaped sheet longitudinal curvature without altering its said hollow cross-sectional shape, and withdrawing said man- drel from said sheet so shaped without altering either its cross-sectional shape or its longitudinal curvature. 10

This specification signed this 27th day of April, 1923.

LEO I. HEINTZ.
